U.S. Appl. No. 29/751,539, filed Sep. 22, 2020, entitled Camera and Speaker Peripheral, by inventors Tanaka et al.

(Continued)

Primary Examiner — Marie D. Fast Horse(74) *Attorney, Agent, or Firm* — Zagorin Cave LLP; Robert W. Holland(57) **CLAIM**

We claim the ornamental design for a speakerphone, as shown and described.

DESCRIPTION

FIG. 1 is a front perspective view of the speakerphone comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

Broken lines shown in the drawings depict portions of the speakerphone that form no part of the claimed design.
